UNITED STATES PATENT OFFICE.

GEORGE L. W. PALMER, OF PLAINFIELD, NEW JERSEY.

PROJECTING APPARATUS.

1,388,193.

Specification of Letters Patent. Patented Aug. 23, 1921.

Application filed January 10, 1920. Serial No. 350,539.

To all whom it may concern:

Be it known that I, GEORGE L. W. PALMER, a citizen of the United States, residing at Plainfield, in the county of Union and State 5 of New Jersey, have invented new and useful Improvements in Projecting Apparatus, of which the following is a specification.

This invention relates to improvements in projecting apparatus.

10 The object of the invention is to provide a simple, automatic apparatus for displaying a series of transparencies, the said apparatus being controlled by the lecturer from a distant point, thereby eliminating the necessity 15 of an attendant who is generally obliged to accompany the lecturer to operate the apparatus.

Another object of the invention is to provide an automatic apparatus which will display 20 a series of transparencies and repeat the display an indefinite number of times without requiring the attention of an attendant.

Still another object of the invention is to provide instrumentalities whereby a container 25 with a plurality of transparencies therein may be brought into position and all of said transparencies presented to the projecting instrumentalities, whereupon the said container will be advanced and succeeded by 30 another container, the operation being repeated for each container.

Still another object of the invention is to provide instrumentalities for presenting the several transparencies to the projecting instrumentalities and for automatically returning 35 said transparencies to their original positions within their respective containers, whereby the display may be repeated continuously in the same order in which it was 40 first presented.

It is still further the object of the invention to provide means for locking the rotary carrier for the transparency containers to prevent the rotation thereof during the interval 45 when the transparencies are being presented to the projecting instrumentalities.

The invention consists in the combination and arrangement of parts whereby the above objects and certain other objects hereinafter 50 appearing may be attained as set forth in the following specification and particularly pointed out in the claims.

Referring to the drawings:

Figure 1 is a vertical section with parts 55 shown in elevation of a projecting apparatus embodying my invention.

Fig. 2 is a vertical section taken on the line 2—2 of Fig. 1, portions thereof being illustrated in elevation.

Fig. 3 is a front elevation as viewed from 60 the direction of the arrow *a*, Fig. 2, of the timing switches for controlling the luminous rays and motor.

Fig. 4 is a detail horizontal section through the light switch, taken on the line 4—4 of 65 Fig. 3, its operating cam being illustrated in connection therewith.

Fig. 5 is a detail horizontal section through the motor switch, taken on the line 5—5 of 70 Fig. 3, its operating cam being illustrated in connection therewith.

Fig. 6 is a horizontal section taken on the line 6—6 of Fig. 2.

Fig. 7 is a diagrammatical representation 75 of the various electrical equipment, together with the various electric circuits connecting the same.

Fig. 8 is an enlarged plan view of the mechanism for rotating the carrier and returning the transparency containers to their 80 initial position, together with the mechanism for locking the rotary carrier to prevent the rotation thereof during the interval when the transparencies are being presented to the projecting instrumentalities. 85

Fig. 9 is a detail vertical section taken on the line 9—9 of Fig. 8.

Fig. 10 is a detail view of the cam which advances the transparency containers step by step. 90

Fig. 11 is a plan view illustrating the rotary carrier, the transparency containers mounted thereon, together with the cam for returning the transparency containers to their initial position. 95

Fig. 12 is a perspective view of a transparency holder with a transparency shown therein.

Fig. 13 is a detail vertical section taken on the line 13—13 of Fig. 8, illustrating the 100 mechanism for rotating the carrier.

Like numerals refer to like parts throughout the several views of the drawings.

In the drawings, 1 designates the instrumentalities for producing luminous rays and in its present embodiment consists of an electric lamp 2 secured to a support 3 which in turn is supported by an insulator block 4. The block 4 is adjustable upon a post 5 to which it is fastened by an adjusting 110 screw 6. The post 5 projects upwardly from a slide 7 which is adjustable upon a plat-

form 8 which is supported by a plurality of standards 9. The above-mentioned parts are all inclosed within a casing 10.

The light producing instrumentalities are arranged to coöperate with suitable lenses to project the luminous rays upon a screen, said lenses preferably embodying a pair of condensing lenses 11 which are located within in a receptacle 12, and the usual projecting lenses which are positioned within a casing 13 all disposed in proper alinement upon the platform 8. The light producing and projecting instrumentalities are constructed and arranged in accordance with the construction usually followed in an apparatus of this nature which is well known to those skilled in the art.

One of the conjugate foci of the lenses of this apparatus is shown at B and into this position the transparencies or slides are moved at certain intervals so as to intercept the rays of light passing through the lenses and result in the projecting of the image or images on said transparencies upon a screen, not shown in the drawings.

As hereinbefore stated, one of the features of this invention is to provide a mechanism for automatically presenting the transparencies to the projecting instrumentalities or, in other words, for successively placing said transparencies in the position indicated at B, Fig. 1. The preferred manner of accomplishing this result is to provide a plurality of transparency containers 14 in which the transparencies 15 are arranged parallel with each other, the containers themselves being disposed about a common axis and revolved about said axis so as to aline with the axis of the rays of light, said axis being indicated by the line A—A, Fig. 1.

The containers 14 are each detachably secured to a rotary carrier 16 preferably consisting of a supporting member 17 which is loosely mounted upon a vertical shaft 18 journaled to rotate in bearings 19 and 20 which are provided in a frame 21 which is mounted upon a base 22. The rotary carrier 16 includes a plurality of rods 23, the said rods preferably being arranged in pairs. There are four pairs of these rods each pair being arranged radially relatively to the shaft 18. A slide 24 is mounted upon each pair of rods 23 to slide radially with respect to the axis of the rotary carrier 16, said slide having lugs 25 which engage the rods 23 of the rotary carrier 16.

The containers 14 are preferably of rectangular form and are provided with a plurality of vertical grooves 26 formed in two opposite sides of said container, each of said grooves being adapted to receive a holder 27, clearly illustrated in Fig. 12, which in turn is adapted to hold one of the transparencies 15.

65 The containers 14 are provided with ledges

28 at the lower end of each groove 26, said ledges engaging the lower edge 29 of said holders and thereby preventing said holders from dropping through the bottom of the container which is otherwise open, while the top of the container is entirely open to permit said holders to be inserted in the grooves 26.

The containers rest upon the slides 24 between oppositely disposed vertical sides 30 and 31 formed integral with said slides. The containers are furthermore cut away at 32 at their lower ends, see Fig. 2, to allow the sides of the container to project below the slide 24.

80 The containers are also locked against vertical movement when in position upon their respective slides by spring catches 33 which are attached to opposite sides of the container, the said catches being provided with a lip 34 which engages a plate 35 fast to each of the sides 30 and 31 of the slide 24, as clearly illustrated in Fig. 1. The containers are therefore prevented from becoming displaced upon the slides either longitudinally, transversely or vertically thereof when the transparencies contained therein are elevated to intercept the rays of light, but at the same time said containers may be readily detached from the slide when it is desired to supply a new set of transparencies therefor.

90 The transparency holders 27 are of skeleton construction and preferably consist of a base portion 36 from which project upright members 37 which are provided with grooves 38 within their inner edges adapted to receive one of the transparencies 15. Upon the outer edge of the upright members 37 is provided a tongue 39 which is adapted to 95 slide vertically in the grooves 26 provided in the transparency container 14.

100 The movement of the rotary carrier 16 is intermittent, thereby providing a rest during the interval when the transparencies 15 of each container 14 are being presented to the projecting instrumentalities, it being understood that all of the transparencies in a container are exposed to said projecting instrumentalities before a succeeding container is moved into position.

110 The mechanism for imparting to the transparency container 14 its step by step advance movement in order that the transparencies therein may be successively presented to the projecting instrumentalities consists of a pair of intermittent gears, commonly known as Geneva gears, consisting of a driven member 40 which is fast to the lower end of the shaft 18 and a driving member 41 which is fast to a vertical shaft 42 adapted to rotate in bearings provided in the frame 21. The driven member 40 is provided with radial slots 43 preferably four in number to correspond with the number of 115

120

125

130

containers 14. The portions of said driven member between said slots are concaved at 44 to correspond with the periphery of the driving member 41, said periphery being circular in form. The driving member 41 in the present instance is adapted to rotate the driven member 40 one quarter of a rotation for each complete rotation of said driving member and for this purpose a pin 45 is located at the proper point and adjacent to the periphery of the driving member to enter the slots 43 in said driven member and thus rotate said member.

The periphery of the driving member 41 is recessed at 46 adjacent to the pin 45 to permit said driving member to be moved when in engagement with said pin, while the curved periphery engaging the concaved portions 44 of said driven member positively 20 prevents the movement of said driven member when said pin is not in engagement therewith. The pin 45 is attached to one face of a gear 47, said gear being attached to the driving member 41. A continuous rotary motion is imparted to the gear 47 through a pair of spur gears 48 and 49, a worm gear 50 and a worm 51. The worm gear 50 and the spur gear 49 are attached to a vertical countershaft 52, while the worm 30 51 is attached to the arbor 53 of an electric motor 54.

Fast to the shaft 18 is a bevel gear 55 which meshes with and drives a bevel pinion 56 fast to a horizontal shaft 57 which is 35 mounted to rotate in brackets 58 and 59 depending from a portion of the frame 21. The relative proportions of the gear 55 and pinion 56 are such that the shaft 57 will make a complete rotation for every quarter 40 rotation on the shaft 18. Fast to the shaft 57 is a cylindrical cam 60, the periphery of which is provided with a groove 61 which makes a plurality of revolutions there-around.

45 Referring to Fig. 10, it will be noticed that the cylindrical cam 60 is provided at its opposite ends with shoulders 62 and 63, the groove 61 starting at the shoulder 62 and extending around the cam to provide for 50 regular intervals of rest as at 64 for a greater part of a revolution and then a quick advance as at 65.

Each slide 24 is provided upon its inner side 31 with a lug 66 in which is mounted a 55 vertically disposed rod 67. The rod 67 is provided at its lower end with a foot 68 which constitutes a follower and this follower is adapted to be engaged by the sides of the cam groove 61. A spring 69 acts to 60 always force the rod 67 together with its foot 68 downwardly.

In Fig. 1 the right hand slide 24 and transparency container 14 are in their initial positions or the positions they occupy when 65 they present the first transparency 15 to the

projecting instrumentalities. At this time the foot 68 is resting upon the shoulder 62 of the cam 60. As the cam 60 turns in the direction of either of the arrows *b*, Figs. 9 and 10, the sides of the groove 61 will engage the foot 68 and impart to the slide 24 and the container 14 mounted thereon a step by step movement radially upon the rods 24, the said movement being equal to the distance between successive transparencies 75 in the container 14.

The arrangement of the gearing previously described is such that each time the cylindrical cam 60 comes to a stop one of the transparencies 15 will be in proper alignment with one of the conjugate foci *B* of the lenses, it then remains for each transparency alining with said location *B* to be moved from its container into a position to intercept the rays of light. For this purpose an elevator 70 is provided, said elevator preferably consisting of a frame 71 to which is secured a pair of vertically disposed rods 72 arranged in alignment with the transparency holder 27 alining with the location *B*. The upper ends of the rods 72 terminate slightly below the lower edge 29 of the transparency holder 27 so as to provide sufficient clearance to permit the carrier to be rotated without interference. The rods 72 reciprocate 85 in bearings in the frame 21 and the frame 71 preferably slides upon fixed guide rods 73 secured at their opposite ends in the frame 21.

A cam lever 74 is pivoted at 75 to a projection 76 formed integral with the frame 100 21. The opposite end of the lever 74 engages a pin 77 projecting from the frame 71. A cam roll 78 is attached to the lever 74 and engages a cylindrical cam 79, the lower end of which is secured to the driving member 105 41 with which it is adapted to rotate. The roll 78 traveling upon the upper end of the cam is adapted to raise the elevator 70 and thus move the holder 27 together with its transparency into intercepting relation with 110 the rays of light, as illustrated in Figs. 1 and 2.

The elevator 70 is returned to its normal position at the proper time by a portion 80 of the cylindrical cam 79, the said portion 115 80 engaging the upper side of the cam roll 78 and forcing said roll downwardly through a slot 81 formed in said cam. The lever 74 is lifted by the inclined edge 82 of the cam. When in its lowermost position, the frame 120 71 rests upon buffers 83 which prevent any noise when said frame reaches the end of its downward movement.

As the holder containing the transparencies is being raised by the elevator the upper 125 edge of the transparencies will engage a weight 84 which is mounted to slide upon vertical rods 85. The upper ends of the rods 85 are tied together by a yoke 86. The weight 84 insures a quick return of the hold-

ers 27 to the containers when the cam lever 74 is retracted and overcomes any tendency which might exist which would cause the holder to stick and prevent it from dropping 5 back into its container.

After a transparency has been moved to the position B where it intercepts the rays of light and the image thereon has been projected upon the screen and the transparencies 10 returned to the container, the cylindrical cam 60 is given one rotation whereupon the next transparency in the container is advanced to the position formerly occupied by the first transparency, whereupon the second 15 transparency will be moved into position to intercept the rays of light after which it is returned to the container and so on until all of the transparencies within a container have been shown upon the screen after which 20 another container will be brought into position, as will be hereinafter described and the transparencies in the second container will be successively presented to the projecting instrumentalities. 25 During the interval when the transparencies 15 are being presented to the projecting instrumentalities, it is desirable to lock the rotary carrier 16 to prevent the rotation thereof. This is accomplished in the following manner:

Referring particularly to Figs. 8 and 9, a substantially circular bed plate 87 is provided which rests upon the frame 21. The bed plate has an opening 88 formed therein 30 through which projects a slight distance the cylindrical cam 60, the upper surface 89 of said bed plate being tangent with the bottom of the groove 61 of the cylindrical cam. Located slightly above the cylindrical cam and 35 fastened to projections formed integral with the bed plate 87 are a pair of guide plates 90 between the adjacent edges of which is provided a slot 91. With the exception of the interval when the foot 68 is resting upon the 40 shoulders 62 and 63 of the cylindrical cam 60, the adjacent edges of the guide plates 90 engage an enlarged portion 92 of the rods 67 at which time the rotary carrier 16 is prevented from moving. When the foot 68 is 45 resting upon the shoulder 62, which is the initial position of the container, the finger 93 formed integral with a slide plate 94 partially surrounds the enlarged portion 92 of the rod 67, while during the interval that 50 the foot is resting upon the shoulder 63, which position is illustrated in dotted lines, Fig. 8, the said dotted position being the final position of the container, a projection 55 96 projects in the path of said enlarged portion 92.

It is evident that it is necessary to move the slide plate 94 in order that each container may be brought into position. This is accomplished by means of a lever 95 pivoted at 60 196 to the bed plate 87. One end of

the lever 95 engages a pin 97 which projects upwardly from the slide plate 94, while the other end of said lever is held by a spring 98 in engagement with a cam 99 which is fast to the upper end of the shaft 42. As 70 the cam 99 is rotated in the direction of the arrow c, Fig. 8, the lever 95 will be suddenly rocked by the drop of the cam at the point 100, thereby causing the slide plate to move toward the right, Fig. 8, being guided by the 75 studs 101 which pass through a slot 102 formed in said slide plate.

When all of the transparencies within a container have been presented to the projecting instrumentalities the carrier 16 is rotated 80 through an angle of 90° moving thereon the before-mentioned container and simultaneously moving another container into position as follows:

Formed upon the upper surface 89 of the 85 bed plate 87 is a cam groove 103. The cam groove at its starting point alines with the shoulder 63 of the cylindrical cam 60 and in effect is a continuation of the cam groove 61, the bottom of the groove 103 being tangent with the bottom of said groove 61. For 90° the groove 103 extends around the surface of the bed plate 87 concentric with the shaft 18 after which it continues for 270° substantially in the form of a spiral terminating in alignment with the shoulder 62 of the cylindrical cam 60. The foot 68 is adapted to slide in the cam groove 103, the enlarged portion 92 of the rod 67 being engaged at the proper time by a rotary pushing device 104, see Figs. 8 and 13. This device consists of a member 105 which is fast to the vertical shaft 18 and rotates intermittently therewith. Mounted in bearings 106 formed upon the underside of the member 105 100 are two oppositely disposed rods 107 each of which is forced continually by springs 108 against the periphery of a stationary cam 109 which is rigidly fastened to the bed plate 87. The cam 109 is provided 105 at 110 with a sudden drop.

As the pushing device 104 is rotated in the direction of the arrow d, Fig. 8, from the position illustrated in dotted lines to that illustrated in full lines, one of the rods 115 107 will engage the portion 92 of the rod 67 which is projecting downwardly from the slide 24 and rotate the carrier 16 through an angle of 90°, at the same time transferring the foot 68 from the shoulder 63 120 of the cylindrical cam 60 to the cam groove 103 on the bed plate 87. As the pushing device comes to a stop at the end of a quarter rotation the rod 107 will be withdrawn from behind the rod 67 by reason of 125 the opposite end of said rod 107 reaching the point 110 of the cam 109 and suddenly being forced inwardly by the spring 108. The pushing device 104 continues to function with each subsequent intermittent ro- 130

tation of the shaft 18 but the carrier will not be again rotated until another container has had its transparencies all presented to the rays of light and has been fed radially 5 by the cylindrical cam 60 into the position where its rod 67 will be engaged by the pushing device, whereupon the movement of the carrier will force the foot 68 of the preceding container along the spiral portion 10 of the cam groove 103 and said container will be moved radially outwardly upon the rods 23. This operation is repeated each intermittent rotation of the carrier advancing the first container 90° and simultaneously 15 moving it still farther outwardly until it is again delivered to its initial position where its transparencies may be again presented to the rays of light.

It is desirable that during the interval 20 when the transparencies are being changed that the rays of light shall be shut off. This is accomplished automatically in coöperation with the mechanism for changing the transparencies as follows:

25 Referring particularly to Figs. 3, 4 and 7, a switch 111 is provided, the said switch embodying in its construction a flexible metallic contact member 112 which is mounted upon an insulator plate 113 and a contact member 114 constructed of graphite which is adjustably mounted in a plate 115 which constitutes a terminal for a wire 116. The terminal plate 115 is fast to the insulating plate 113. The graphite of which the contact member 114 is constructed acts as a condenser to reduce the spark as the contacts make and break. The contact member 112 is connected to a plate 117 by screws 118, the said plate constituting a terminal for a wire 40 119. The wire 116 connects the terminal plate 115 directly with the electric lamp 2. Another wire 120 connects the electric lamp 2 with the line wire 121, while the wire 119 connects the terminal plate 117 with a second line wire 122. The line wires 121 and 122 are connected to a suitable source of electric supply. A disk 123 constructed of insulating material is fast to the shaft 42 and rotates therewith. The periphery of the disk 123 is adapted to engage the flexible contact member 112 at the proper time and force the same into contact with the contact member 114, thereby completing an electric circuit which includes a line wire 121, wire 50 120, electric lamp 2, wire 116, switch 111, wire 119 and line wire 122 thus lighting the electric lamp 2. When, however, the circuit through the switch 111 is broken by reason of a portion of the periphery of the disk 123 being cut away at 124, the rays of light will be extinguished and will remain so a sufficient length of time to permit the changing of the transparencies.

As hereinbefore stated one of the novel 65 features of this invention is that it may be

controlled by the lecturer exhibiting the transparencies from his station which may be upon the platform or some other convenient place which may be at some distance from the point where the apparatus is located. This is accomplished as follows:

Referring particularly to Figs. 3, 5 and 7, a switch 125 is provided similar to the switch 111. This switch also embodies in its construction a flexible metallic contact member 126 which is also mounted upon the insulating plate 113, and a screw 127 constituting a second contact member which is adjustably mounted in a plate 128 which constitutes a terminal for a wire 129. The plate 128 is fast to the insulating plate 113. The contact member 126 is connected to a plate 130 by screws 131, the said plate 130 constituting a terminal for a wire 132. The wire 129 connects the terminal plate 128 with the line wire 122. The wire 132 connects the terminal plate 130 directly with the terminal 133 of the electric motor 54, while a wire 134 connects the other terminal 135 of said motor with the line wire 121. 90 A disk 136 constructed of insulating material is fast to the shaft 42 and rotates therewith. The periphery of the disk 136 is adapted to engage the flexible contact member 126 to force the same into contact with the contact member 127. The periphery of the disk 136 is also provided with a cutaway portion 137. The contact of the members 126 and 127 may or may not complete an electric circuit as will be herein-after fully explained.

Conveniently located upon the base 22 of the apparatus is a switch 138. This switch embodies in its construction flexible contact members 139 and 140 and a post 141, all insulated from each other. The members 139 and 140 normally contact with the post 141. A wire 142 connects the member 139 with the terminal plate 128, while another wire 143 connects the member 140 with the terminal plate 130. A plug 144 having contact pins 145 and 146 is adapted to engage the contact members 139 and 140 and force said members out of engagement with the post 141, thereby breaking the electric circuit 110 which at times is completed through said members and the post 141. The pins 145 and 146 are connected by wires 147 and 148 respectively to a switch 149 of well-known construction which is held by the lecturer 115 and which is operated by a push button 150. The lower portion of the apparatus is enclosed within a sheet metal casing 151.

During the operation of the device when the same is being used for lecture purposes 125 the lecturer desires that a transparency may be thrown upon the screen, not shown, and remain upon said screen indefinitely while he is delivering that portion of his lecture which refers to the picture which is being 130

exhibited. In order that this picture may remain indefinitely upon the screen, the motor 54 must be stopped at a certain point by breaking the electric circuit which includes 5 the motor. During the period that the motor is running this circuit includes the wires 121 and 134, the motor 54, wire 132, switch 125 and wires 129 and 122, the contact members 126 and 127 of the switch 125 being 10 held in engagement with each other by the disk 136. The motor will continue to run until the contact members 126 and 127 are disengaged by reason of the break in the periphery of the disk 136 caused by the cut- 15 away portion 137. During this time the light circuit remains unbroken. To again start the motor, the lecturer must press the button 150 of the switch 149. This will complete a circuit which includes the wires 20 121 and 134, motor 54, wire 132, terminal plate 130, wire 143, contact member 140, pin 146, wire 148, switch 149, wire 147, pin 145, contact member 139, wire 142, terminal plate 128 and the wires 129 and 122, see Fig. 7. 25 It is necessary for the lecturer to push continually upon the button 150 for a short period of time to enable the motor 54 to rotate the disk 136 to a point where its periphery will again engage the flexible contact member 126 and again complete the circuit 30 through the switch 125.

During the interval when the lecturer is manually operating the switch 149 to complete the motor circuit, the electric light circuit will be broken through the switch 111 and during the period that said electric light circuit remains broken a new transparency will automatically be brought into position ready to be thrown upon the screen when 35 said circuit is again completed. When the motor circuit is again completed through the switch 125 the lecturer may release the button 150 and the motor will continue to run until the circuit through the switch 125 40 is again broken. If the lecturer releases the button 150 too soon, he will be made aware of the fact by the non-appearance of the succeeding transparency and a further pressure on said button is necessitated. 45

When it is not desired to use the device for lecture purposes, but rather for displaying advertising matter and it is desired that the operation shall be entirely automatic and in no way controlled by an attendant, the 50 plug 144 is removed. This will allow the contact members 139 and 140 to engage the post 141, the result being that an electric circuit which includes the motor will always be completed allowing the motor to run con- 55 tinuously in spite of the fact that the disk 136 and switch mechanism 125 continue to function. This circuit includes the wires 121 and 134, motor 54, wire 132, terminal plate 130, wire 143, contact member 140, 60 post 141, contact member 139, wire 142, ter-

70 minal plate 128 and the wires 129 and 122. The circuit never passes through the switch 125.

During the general operation of the apparatus hereinbefore specifically described all 75 of the transparencies in the first container are thrown upon the screen, the carrier is then rotated one quarter of a turn and all of the transparencies of the second container are thrown upon the screen and this operation is continued until all of the transparencies have been successively presented to the rays of light after which the operation is repeated indefinitely if desired, or other containers with new sets of transparencies 80 may be inserted in their place upon the carrier and operate in the same manner.

While I have herein shown and described the preferred embodiment of my invention for the purpose of illustration, it is to be understood that the invention is not limited to the mere details or relative arrangement of the parts or to the specific applications herein shown, as extensive alterations may be made in the illustrated form and embodiment of the invention without departing 90 from the principle thereof.

Having thus described my invention what I claim and desire to secure by Letters Patent is:

1. A projecting apparatus having, in combination, instrumentalities for projecting luminous rays, a carrier constructed and arranged to rotate in a plane substantially parallel with the axis of said rays, a plurality of transparency containers mounted upon said carrier each adapted to hold a plurality of transparencies, means to feed said transparencies consecutively from each of said containers into the path of said rays, 105 and means to move said carrier after a plurality of transparencies have been fed consecutively from a container into the path of said rays.

2. A projecting apparatus having, in combination, instrumentalities for projecting luminous rays, a carrier constructed and arranged to rotate in a plane substantially parallel with the axis of said rays, a plurality of transparency containers mounted upon said carrier each adapted to hold a plurality of transparencies in substantially lateral relation to the axis of said rays, means to feed said transparencies consecutively from each of said containers into the path of said rays, 115 and means to move said carrier after a plurality of transparencies have been fed consecutively from a container into the path of said rays.

3. A projecting apparatus having, in combination, instrumentalities for projecting luminous rays, a carrier constructed and arranged to rotate in a plane substantially parallel with the axis of said rays, a plurality of transparency containers, means for 125

supporting a plurality of sets of parallelly disposed transparencies in said containers, means to feed said transparencies one by one consecutively from each of said containers 5 into the path of said rays, and means to move said carrier after all of the transparencies of a container have been fed into the path of said rays.

4. A projecting apparatus having, in combination, instrumentalities for projecting luminous rays, a carrier constructed and arranged to rotate in a plane substantially parallel with the axis of said rays, a plurality of transparency containers, each 10 adapted to hold a plurality of transparencies in parallel relation, means to feed said transparencies one by one consecutively from each of said containers into the path 15 of said rays and mechanism for intermittently rotating said carrier to move each of 20 said containers into a plane of said luminous rays after a plurality of the transparencies of one of said containers have been presented to said rays.

5. A projecting apparatus having, in combination, instrumentalities for projecting luminous rays, a carrier constructed and arranged to rotate in a plane substantially parallel with the axis of said rays, a plurality 30 of transparency containers mounted upon said carrier, each adapted to hold a plurality of transparencies, means to move said containers radially with respect to the axis of said carrier to successively position the 35 transparencies in said containers in a predetermined position relatively to said projecting instrumentalities, means to feed said transparencies into the path of said rays, and means to move said carrier after a plurality 40 of the transparencies of a container have been fed consecutively from said container into the path of said rays.

6. A projecting apparatus having, in combination, instrumentalities for projecting 45 luminous rays, a carrier constructed and arranged to rotate in a plane substantially parallel with the axis of said rays, a plurality of transparency containers mounted upon said carrier, each adapted to hold a plurality 50 of transparencies, means to intermittently move each of said containers radially upon said carrier to successively position the transparencies in said containers in a predetermined position relatively to said 55 projecting instrumentalities, means to feed said transparencies consecutively from each of said containers into the path of said rays, and means to intermittently rotate said carrier after a plurality of the transparencies 60 of a container have been fed consecutively from said container into the path of said rays.

7. A projecting apparatus having, in combination, instrumentalities for projecting 65 luminous rays, a carrier constructed and ar-

ranged to rotate in a plane substantially parallel with the axis of said rays, a plurality of transparency containers mounted upon said carrier, each adapted to hold a plurality of transparencies, means to move 70 each of said containers radially upon said carrier, an elevator adapted to align with one of the transparencies in a container when said container is in a plane containing the axis of said luminous rays, means for 75 operating said elevator to engage said transparencies and move the same one by one consecutively from said container into the path of said rays and means to rotate said carrier after a plurality of the transparencies of a container have been fed consecutively from said container into the path of 80 said rays.

8. A projecting apparatus having, in combination, instrumentalities for projecting 85 luminous rays, a carrier constructed and arranged to rotate in a plane substantially parallel with the axis of said rays, a plurality of transparency containers mounted upon said carrier, each adapted to hold a 90 plurality of transparencies, means to move each of said containers radially upon said carrier, an elevator adapted to align with one of the transparencies in a container when said container is in a plane containing 95 the axis of said luminous rays, means for operating said elevator to engage a transparency alining therewith and for moving said transparencies consecutively from said container into intercepting relation with 100 said rays, means for returning said transparencies to said container upon the withdrawal of said elevator, and means to move said carrier after a plurality of transparencies have been fed consecutively from said 105 container into the path of said rays and back into said container.

9. A projecting apparatus having, in combination, instrumentalities for projecting 110 luminous rays, a carrier constructed and arranged to rotate in a plane substantially parallel with the axis of said rays, a plurality of transparency containers mounted upon said carrier, each adapted to hold a plurality of transparencies, a rotary cylindrical cam, followers coöperating with said cam adapted to move said containers radially with respect to the axis of said carrier, means to feed said transparencies one by one consecutively from each of said containers into the path of said rays, and means to rotate said carrier. 115

10. A projecting apparatus having, in combination, instrumentalities for projecting 120 luminous rays, a carrier constructed and arranged to rotate in a plane substantially parallel with the axis of said rays, a plurality of transparency containers mounted upon said carrier each adapted to hold a plurality of transparencies, a rotary cylind- 125

130

drical cam, means coöperating with said cam adapted to intermittently move said container radially with respect to the axis of said carrier, means to feed said trans-
5 parencies consecutively from each of said containers into the path of said rays, and means to rotate said carrier.

11. A projecting apparatus having, in combination, instrumentalities for project-
10 ing luminous rays, a carrier constructed and arranged to rotate in a plane substan-
tially parallel with the axis of said rays, a plurality of transparency containers mounted upon said carrier each adapted to hold a
15 plurality of transparencies, a rotary cylind-
rical cam, means coöperating with said cam adapted to intermittently move said container radially with respect to the axis of said carrier, means to feed said trans-
20 parencies consecutively from each of said containers into the path of said rays, means to lock said carrier to prevent the rotation thereof during the interval in which the transparencies of a container are being fed
25 to said rays, and means to rotate said car-
rier.

12. A projecting apparatus having, in combination, instrumentalities for project-
30 ing luminous rays, a carrier constructed and arranged to rotate in a plane substan-
tially parallel with the axis of said rays, a plurality of transparency containers mounted upon said carrier each adapted to hold a plurality of transparencies, a rotary cylind-
35 rical cam, means coöperating with said cam adapted to intermittently move said container radially with respect to the axis of said carrier, means to feed said trans-
parencies consecutively from each of said
40 containers into the path of said rays, means to lock said carrier to prevent the rotation thereof during the interval in which the transparencies of a container are being fed to said rays, means to release said carrier
45 after a plurality of the transparencies of a container have been fed to said rays, and means to rotate said carrier.

13. A projecting apparatus having, in combination, instrumentalities for project-
50 ing luminous rays, a carrier constructed and arranged to rotate in a plane substan-
tially parallel with the axis of said rays, a plurality of transparency containers mounted upon said carrier each adapted to hold a plurality of transparencies, a rotary cylind-
55 rical cam, means coöperating with said cam adapted to intermittently move said containers radially with respect to the axis of said carrier, means to feed said transparen-
60 cies consecutively from each of said containers into the path of said rays, means to lock said carrier to prevent the rotation thereof during the interval in which the transparencies of a container are being fed
65 to said rays, means to release said carrier

after a plurality of the transparencies of a container have been fed to said rays, and a pusher adapted to intermittently rotate said carrier.

14. A projecting apparatus having, in combination, instrumentalities for project-
70 ing luminous rays, a carrier constructed and arranged to rotate in a plane substantially parallel with the axis of said rays, a plurality of transparency containers mounted upon said carrier each adapted to hold a plurality of transparencies, a rotary cylind-
75 rical cam, means coöperating with said cam adapted to intermittently move said container radially with respect to the axis of said carrier, means to feed said transparencies consecutively from each of said containers into the path of said rays, means to lock said carrier to prevent the rotation thereof during the interval in which the transparencies of a container are being fed to said rays, a
80 pusher adapted to intermittently rotate said carrier, and means to move said container radially outwardly upon said carrier during the rotation thereof.

15. A projecting apparatus having, in combination, instrumentalities for project-
95 ing luminous rays, a carrier constructed and arranged to rotate in a plane substantially parallel with the axis of said rays, a plurality of transparency containers mounted upon said container each adapted to hold a plurality of transparencies, a rotary cylind-
100 rical cam, followers coöperating with said cam adapted to move said containers inward radially with respect to the axis of said carrier, means to feed said transparencies consecutively from each of said containers into the path of said rays, means to intermit-
105 tently rotate said carrier, and a stationary cam adapted to coöperate with said followers to move said containers radially outward upon said carrier during the rotation thereof.

16. A projecting apparatus having, in combination, instrumentalities for project-
115 ing luminous rays, a carrier constructed and arranged to rotate in a plane substantially parallel with the axis of said rays, a plurality of transparency containers mounted upon said container each adapted to hold a plurality of transparencies, a rotary cylind-
120 rical cam, followers coöperating with said cam adapted to move said containers inward radially with respect to the axis of said carrier, means to feed said transparencies consecutively from each of said containers into the path of said rays, a stationary cam, means to simultaneously rotate said carrier and transfer a follower from said rotary cylindrical cam to said stationary cam, whereby said containers may be moved ra-
125 130

dially outward upon said carrier during the rotation thereof.

17. A projecting apparatus having, in combination, instrumentalities for projecting luminous rays, a rotary carrier, a plurality of transparency containers supported by said carrier, mechanism for rotating said carrier to move the several containers supported thereby into a plane containing the axis of said rays, a cam adapted to coöperate with said containers when said carrier is at rest to effect a step by step movement of each of said containers radially with respect to the axis of said carrier, and means for moving all the transparencies in the container lying in the plane containing the axis of said luminous rays to intercept said rays one by one consecutively.

18. An apparatus of the class described having, in combination, a rotary carrier, means for rotating said carrier, a plurality of slides supported upon said carrier to move radially relatively to the axis thereof, a transparency container detachably mounted upon each of said slides, means for imparting to each of said slides successively an intermittent radial inward movement when said carrier is at rest, and means for returning said slides to their initial positions.

19. An apparatus of the class described having, in combination, a rotary carrier, means for intermittently rotating said carrier, a plurality of slides supported upon said carrier to move radially relatively to the axis thereof, a transparency container detachably mounted upon each of said slides, means for imparting to each of said slides successively an intermittent radial inward movement when said carrier is at rest, and means also for imparting to said slides a radial outward movement during the rotary movements of said carrier.

20. An apparatus of the class described having, in combination, a carrier, a plurality of slides supported upon said carrier to move radially relatively to the axis thereof, a transparency container detachably mounted upon each of said slides, a rotary cylindrical cam, vertical rods yieldingly mounted in said slides, a follower for each of said vertical rods adapted to coöperate with said cam to impart an intermittent radial inward movement to said slides, a pusher, horizontally disposed rods thereon, means to force said horizontal rods into engagement with said vertical rods, and means to intermittently rotate said pusher whereby a rotary motion may be imparted through said slides to said carrier.

21. An apparatus of the class described having, in combination, a carrier, a plurality of slides supported upon said carrier to move radially relatively to the axis thereof, a transparency container detachably mounted upon each of said slides, a rotary cylindrical

cam, vertical rods yieldingly mounted in said slides, a follower for each of said vertical rods adapted to coöperate with said cam to impart an intermittent radial inward movement to said slides, a pusher, horizontally disposed rods thereon, means to force said horizontal rods into engagement with said vertical rods, means to intermittently rotate said pusher, and means to disengage said horizontal rods from said vertical rods at the end of said intermittent movement.

22. An apparatus of the class described having, in combination, a carrier, a plurality of slides supported upon said carrier to move radially relatively to the axis thereof, a transparency container detachably mounted upon each of said slides, a rotary pusher, a rotary cylindrical cam, vertical rods yieldingly mounted in said slides, a follower for each of said vertical rods adapted to coöperate with said cam to impart an intermittent radial inward movement to said slides, the final of said inward movements forcing said slide into the path of the pushing instrumentalities, and means to rotate said pusher.

23. An apparatus of the class described having, in combination, a carrier, a plurality of slides supported upon said carrier to move radially relatively to the axis thereof, a transparency container detachably mounted upon each of said slides, a rotary pusher, a rotary cylindrical cam, vertical rods yieldingly mounted in said slides, a follower for each of said vertical rods adapted to coöperate with said cam to impart an intermittent radial inward movement to said slides, the final of said inward movements forcing said slide into the path of the pushing instrumentalities, means to rotate said pusher through an angle of 90°, and means to automatically withdraw the pushing instrumentalities from engagement with said slide.

24. An apparatus of the class described having, in combination, a carrier, a plurality of slides supported upon said carrier to move radially relatively to the axis thereof, a transparency container detachably mounted upon each of said slides, a rotary cylindrical cam, vertical rods yieldingly mounted in said slides, a follower for each of said vertical rods adapted to coöperate with said cam to impart an intermittent inward rotary movement to said slides, a pusher, horizontal rods thereon, a stationary cam adapted to force said horizontal rods into engagement with said vertical rods, means to intermittently rotate said pusher whereby a rotary motion may be imparted through said slide to said carrier, and springs adapted to force said horizontal rods out of engagement with said vertical rods at the end of the intermittent movement of said pusher.

25. A projecting apparatus having, in

combination, instrumentalities for projecting rays of light, a carrier constructed and arranged to rotate in a plane substantially parallel with the axis of said rays, a plurality of transparency containers mounted upon said carrier each adapted to hold a plurality of transparencies, means to feed said transparencies one by one consecutively from each of said containers into the path 10 of said rays, means to automatically extinguish said rays of light during the feeding of each transparency, and means to rotate said carrier after a plurality of the transparencies of a container have been fed consecutively into the path of said rays.

26. A projecting apparatus having, in combination, instrumentalities for projecting rays of light, a carrier constructed and arranged to rotate in a plane substantially 20 parallel with the axis of said rays, a motor adapted to furnish the motive power for said apparatus, a plurality of transparency containers mounted upon said carrier each adapted to hold a plurality of transparencies, means to feed said transparencies consecutively from each of said containers into the path of said rays, and means to automatically stop said motor while a transparency is exposed to said rays, whereby 30 said transparency may remain indefinitely in the path of said rays.

27. A projecting apparatus having, in combination, instrumentalities for projecting rays of light, a carrier constructed and arranged to rotate in a plane substantially 35 parallel with the axis of said rays, a motor adapted to furnish the motive power for said apparatus, a plurality of transparency containers mounted upon said carrier each 40 adapted to hold a plurality of transparencies, means to feed said transparencies consecutively from each of said containers into the path of said rays, means to automatically stop said motor while a transparency 45 is exposed to said rays whereby said transparency may remain indefinitely in the path of said rays, and manually operated means adapted to start said motor.

28. A projecting apparatus having, in combination, instrumentalities for projecting rays of light, a carrier constructed and arranged to rotate in a plane substantially 50 parallel with the axis of said rays, a motor adapted to furnish the motive power for said apparatus, a plurality of transparency containers mounted upon said carrier each 55 adapted to hold a plurality of transparencies, means to feed said transparencies consecutively from each of said containers 60 into the path of said rays, means to automatically stop said motor while a transparency is exposed to said rays, whereby said transparency may remain indefinitely in the path of said rays, manually operated 65 means adapted to start said motor, and

means to automatically extinguish said rays of light during the feeding movement of said transparencies.

29. A projecting apparatus having, in combination, instrumentalities for projecting rays of light, a carrier constructed and arranged to rotate in a plane substantially parallel with the axis of said rays, a plurality of transparency containers mounted upon said carrier, each adapted to hold a 70 plurality of transparencies, means to feed said transparencies one by one consecutively from each of said containers into the path of said rays, a switch adapted to automatically shut off said rays of light previous to 75 the removal of a transparency from the path of the rays of light and to automatically turn on said rays of light after a transparency has been positioned to intercept said rays of light, and means to rotate said 80 carrier after a plurality of the transparencies of a container have been fed consecutively into the path of said rays of light.

30. A projecting apparatus having, in combination, a lens, instrumentalities for projecting rays of light through said lens, a rotary carrier adapted to revolve in a plane substantially parallel with said rays of light, a plurality of pairs of radial rods, a slide mounted upon each of said pairs of rods, a transparency container detachably mounted upon each of said slides adapted to contain a plurality of transparencies, means for intermittently rotating said carrier to successively move said containers into a position beneath and in a plane containing the axis of said rays of light, means for imparting to each of said slides an intermittent radial inward movement between the rotary movements of said carrier to successively align the transparencies carried thereby with the optical center of said lens, and means for lifting the transparency alining with said optical center into a position to intercept said rays of light.

31. A projecting apparatus having, in combination, a lens, instrumentalities for projecting rays of light through said lens, a rotary carrier adapted to revolve in a plane substantially parallel with said rays of light, a plurality of pairs of radial rods, a slide mounted upon each of said pairs of rods, a transparency container detachably mounted upon each of said slides adapted to contain a plurality of transparencies, means for intermittently rotating said carrier to successively move said containers into a position beneath and in a plane containing the axis of said rays of light, means for imparting to each of said slides an intermittent radial inward movement between the rotary movements of said carrier to successively align the transparencies carried thereby with the optical center of said lens, means for lifting the transparency alining with 115

said optical center into a position to intercept said rays of light, and a switch adapted to automatically shut off and turn on said rays of light.

- 5 32. A projecting apparatus having, in combination, a lens, instrumentalities for projecting rays of light through said lens, a rotary carrier adapted to revolve in a plane substantially parallel with said rays of light, a plurality of pairs of radial rods, a slide 40 mounted upon each of said pairs of rods, a transparency container detachably mounted upon each of said slides adapted to contain a plurality of transparencies, a motor adapted to furnish the motive power for said apparatus, means for intermittently rotating said carrier to successively move said containers into a position beneath and in a plane containing the axis of said rays of light, means for imparting to each of said 45 slides an intermittent radial inward movement between the radial movements of said carrier to successively align the transparencies carried thereby with the optical center of said lens, means for lifting the transparency 50 alining with said optical center into a position to intercept said rays of light, a switch adapted to automatically shut off and turn on said rays of light, a second switch adapted to automatically stop said motor 55 while a transparency is exposed to said rays of light, whereby said transparency may remain indefinitely in the path of said rays of light, and manually operated means adapted to start said motor. 60
- 65
- 30 33. A projecting apparatus having, in combination, a lens, instrumentalities for

projecting rays of light through said lens, a rotary carrier adapted to revolve in a plane substantially parallel with said rays of light, a plurality of pairs of radial rods, a slide 40 mounted upon each of said pairs of rods, a transparency container detachably mounted upon each of said slides adapted to contain a plurality of transparencies, a motor adapted to furnish the motive power for said apparatus, means for intermittently rotating said carrier to successively move said containers into a position beneath and in a plane containing the axis of said rays of light, means for imparting to each of said 50 slides an intermittent radial inward movement between the radial movements of said carrier to successively align the transparencies carried thereby with the optical center of said lens, means for lifting the transparency 55 alining with said optical center into a position to intercept said rays of light, a switch adapted to automatically shut off and turn on said rays of light, a second switch adapted to automatically stop said motor while a transparency is exposed to said rays of light, whereby said transparency may remain indefinitely in the path of said rays of light, and manually operated means adapted to start said motor.

In testimony whereof I have hereunto set my hand in presence of two subscribing witnesses.

GEORGE L. W. PALMER.
